UNITED STATES PATENT OFFICE

163,677

AUTOMOTIVE TRUCK

George U. Brumbaugh, Palo Alto, Calif., assignor
to Peterbilt Motors Company, Oakland, Calif.,
a corporation of California

Application April 17, 1950, Serial No. 9,264

Term of patent 14 years

(Cl. D14—3)

To all whom it may concern:

Be it known that I, George U. Brumbaugh, a citizen of the United States, residing at Palo Alto, State of California, have invented a new, original, and ornamental Design for Automotive Truck, of which the following is a specification, reference being had to the accompanying drawing, forming a part hereof.

Fig. 1 is a view in perspective of an automotive truck, looking from the front and one side, showing my new design; and

Fig. 2 is a view in perspective of the same, looking from the front.

I claim:

The ornamental design for an automotive truck, substantially as shown.

GEORGE U. BRUMBAUGH.
